UNITED STATES PATENT OFFICE.

ERIK GUSTAF NICOLAUS SALENIUS, OF STOCKHOLM, SWEDEN, ASSIGNOR TO
THE AKTIEBOLAGET RADIATOR, OF SAME PLACE.

CENTRIFUGAL APPARATUS.

SPECIFICATION forming part of Letters Patent No. 551,511, dated December 17, 1895.

Application filed June 15, 1894. Serial No. 514,691. (No model.) Patented in France January 30, 1894, No. 235,924, and in England June 5, 1894, No. 10,944.

To all whom it may concern:

Be it known that I, ERIK GUSTAF NICOLAUS SALENIUS, a subject of the King of Sweden and Norway, residing at Stockholm, Sweden, have invented certain new and useful improvements in Centrifugal Apparatuses, (for which a patent has been granted to me in France, dated January 30, 1894, No. 235,924, and in Great Britain, dated June 5, 1894, No. 10,944,) of which the following is a specification.

This invention relates particularly to the fastening of the lid or cover on a centrifugal drum in such a way that the lid will always occupy the same position on the drum. Hitherto it has been customary to secure the lid directly to the drum by screwing it on the same. The screw-threads, however, soon become worn, and even when this does not prevent the lid from being tightened in the usual way it generally has the result that the lid, after being tightened, sits unevenly or in an oblique position on the drum. This fault, which the workman managing the apparatus cannot correct, is very prejudicial to the motion of the drum as well as the separating operation, as it not only disturbs the centering of the drum, but changes the distance of the cream-outlet (on the lid) from the drum axis.

The object of this invention is to improve the fastenings of the lid in such a way that screw-threads on the same are avoided, and this is effected by simply pressing the lid closely to the drum by means of a number of attachment-screws, which are in some convenient way united with the lid or with the drum. These screws may be arranged as shown on the accompanying drawings, where-in—

Figure 1 is a vertical mid-section of the drum and cover, and Fig. 2 is a plan view of same, partly broken away to show the construction of the fastenings. Fig. 3 is a section similar to Fig. 1, illustrating a modified construction of the upper part of the lid.

A represents the drum and B the lid or top part thereof. On the under side of the lid is a pendent guiding-flange b, which enters the drum, the margin of the lid resting on the upper margin of the drum. Where they

rest, the one on the other, the lid and drum are grooved to receive the usual packing-ring p.

Around the margin of the upper part of the drum A are formed projecting lugs a, preferably equally spaced, and on the lower part of a locking-ring C, adapted to snugly embrace the upper part of the drum, are formed similar spaced lugs c, which project inwardly, and when the ring C is in place these lugs c may be made to take under the respective lugs a on the drum by a partial rotation of the ring. At its upper edge the ring C has an inwardly-projecting flange c^x, which takes over the margin of the lid B, and in this flange are driven set-screws s, which bear or impinge on the lid B and serve to press it down firmly on the packing-ring p and the drum.

In assembling the parts, the packing-ring is placed on the top of the drum, the lid B placed evenly thereon, and the ring C then placed in position. To do this, the lugs c on the ring are made to pass down between the lugs a on the drum. The ring C is then turned so as to bring the lugs c under the lugs a, and the set-screws s are driven down firmly on the lid.

The top part or lid B is necessarily open at the center, thus making it necessary to employ marginal securing devices.

The upper portion of the lid or top part B may be shaped in any manner required, the form depending on the use to which the drum is to be put. Fig. 3, for example, shows a form somewhat different in this respect from that shown in Fig. 1.

The bottom of the drum, if it is desired that the same be removable, may be secured by the same means as that employed for the lid or top part B.

Having thus described my invention, I claim—

1. The combination with a drum of a centrifugal apparatus, and a cover or top-part B, which rests on the drum, of a loose locking ring detachably engaging projecting parts on the drum and having an inturned flange which takes over the margin of said lid, and set-screws in said flange on the ring, which

screws bear on the upper face of the flange on the lid, substantially as set forth.

2. The combination with a drum A, having spaced lugs a, and a ring C, having spaced 5 lugs c, which interengage when the ring is in position on the drum, of the cover B, the margin of which takes under the upper flange on the ring, and the set-screws, screwed through the upper flange of the ring and bearing on

the margin of the cover, substantially as set forth.

In witness whereof I have hereunto signed my name in the presence of two subscribing witnesses.

ERIK GUSTAF NICOLAUS SALENIUS.
